WATER FLOW DETECTOR AND ALARM
MEANSClarence C. Johnson, New York, N. Y., assignor to
American District Telegraph Company, Jersey
City, N. J., a corporation of New Jersey

Application June 23, 1933, Serial No. 677,202

6 Claims. (Cl. 169—23)

This invention relates to water-flow detectors and alarms for water-flow-operated sprinkler systems, and more particularly to a water flow detector having operating means for an electric alarm system for causing an alarm when sprinkler heads discharge, and for preventing alarm from water-hammer in the sprinkler system.

Said detector comprises riser-pressure operated means communicating with an intermediate part of the riser of the sprinkler system and adapted to control an alarm operating means operated by the pressure-operated means when the pressure in the conduit decreases as when the sprinkler heads are discharging during fire, and held against operation when the pressure in the conduit increases, as by water hammer.

Said detector includes a surge passage communicating with the riser or other conduit and provided with an air chamber portion at its outer part, and a diaphragm disposed across the passage between the riser and said chamber portion and adapted to control an alarm operating lever connected to an active portion of the diaphragm, and adapted to operate the alarm only when pressure decreases at the side of the diaphragm nearest the riser. A by-pass establishes communication with the passage at opposite sides of the diaphragm and is provided with a restricted flow retarding means for establishing equilibrium in the system.

In devices of this kind it is desirable at times to remove the restricting means as for cleaning or adjustment; and objects of the present invention are to provide a flow detector of the kind noted having an improved removable restricting means for retarding pressure flow toward the air chamber, and cut-off valves for cutting off the restricting means from other parts of the apparatus before removing the restricting means.

Other objects are to provide signal controlling means for normally preventing tampering with the detector, and notifying as to whether the detector has been put in operative condition.

Another object of the invention is to provide an arrangement whereby a false alarm will not be sent, by the detector of a conduit from which there is no sprinkler discharge, when there is lowered pressure caused by discharge in a nearby communicating conduit.

Other objects of the invention are to improve generally the simplicity and efficiency of such devices and to provide a simple device or apparatus of this kind which is economical, durable, sensitive and very reliable in operation, and economical to manufacture and install.

Still other objects of the invention will appear as the description proceeds; and while herein details of the invention are described in the specification and some of the claims, the invention is not limited to these, since many and various changes may be made without departing from the scope of the invention as claimed in the broader claims. 5

The inventive features for accomplishing these and other objects are shown herein in connection with an improved flow detector which, briefly stated, includes a diaphragm chamber, an air chamber and a conduit connecting said chambers with a riser. One of said conduits has therein a constricting means removable through a plugged opening to the exterior of the conduit. Cut-off valves in the conduit respectively at both sides of the constricting means allow the constricting means to be removed without draining the chambers, and allow the air chamber to be drained 20 without draining the inner portion of the diaphragm chamber. 15

Means secured to said diaphragm operate an exterior switch which may control a signal system. A removable tamper-preventing housing received over said valves and switch has therein a signal controlling tamper-switch held inaccessible in non-alarm condition by said housing when the housing is closed in place. 25

Said valves are so positioned and held as to prevent said housing from being positioned in place when one of the valves or said restricting means is not left in position for normal operation of the flow detector. 30

In the accompanying drawings showing, by way of example, two of many possible embodiments of the invention.

Fig. 1 is a side elevation showing a water flow detector attached to a riser of a sprinkler system;

Fig. 2 is a fragmental end elevation, partly in section on the line 2—2 of Fig. 1;

Fig. 3 is a fragmental plan, partly in horizontal axial section;

Fig. 10 is a diagram showing detectors and alarm relay circuit;

Figs. 11 to 14 are diagrammatic views similar to Fig. 5, and show alternative forms of the invention;

Fig. 15 shows a section taken on the line 15—15 of Fig. 14; and

Fig. 16 is a side elevation of the valve of Figs. 14 and 15.

My invention is shown in Figs. 1 and 5 in combination with a conduit or riser 10 for a sprinkler system (not shown) having branch pipes supplied by the riser and having sprinkler heads. A single surge conduit 14 communicates with the riser above the city check valve 15.

A few elements of the flow-detector will first be pointed out, after which the features of the invention will be described in detail.

Briefly indicated, the detector includes a diaphragm chamber 22, 23 (Fig. 8) having a diaphragm 26 thereacross dividing the chamber into inner and outer chamber portions, the inner portion 22 being connected by the surge conduit 14 with the riser 10, the outer chamber portion 23 being connected by an outer passage 35, 34, 39 with an air chamber 40 (Fig. 5).

A by-pass conduit 43, 47, 46, 44 connects said surge conduit and outer passage and has therein a constricting means 52, 59, 60, removable through a plugged opening to the exterior of the by-pass. Cut-off valves 67, 68 in the by-pass conduit respectively at both sides of the constricting valve allow the constricting means to be removed without draining the chambers, and allow the air chamber to be drained without draining the inner chamber portion.

Means 80, 83, 94 operated by said diaphragm operate switches 100, 101 which may control a signal system. A removable tamper-preventing housing 104, 105 received over said valves and switch has therein a tamper-switch 118 (Fig. 2) and adapted when open to send an alarm and to be held inaccessible in closed non-alarm condition by said housing when the housing is closed in place. Said valves and constricting means are so positioned and held as to prevent said housing from being positioned in place when the handle 16 in one, or both of the cut-off valves is left in projecting cut-off position or when said constricting means is left out of its restricting position.

Now the flow detector will be described in detail.

My improved water flow detector comprises an inner member 18 (Fig. 1) and an outer member 19. The inner member comprises a vertical disk-shaped chamber-wall portion 20 concaved at its inner face 21 (Fig. 8) to form the inner portion 22 of a diaphragm chamber 22, 23, said inner portion communicating with the single surge conduit 14 coaxial with said chamber portion and communicating with the riser above or below the valve, preferably above. Said outer member 19 is provided at its inner end with a concaved disk shaped flange portion 25 adjacent said first named disk-shaped portion 20 to form the disk shaped diaphragm chamber 22, 23.

A diaphragm 26 (Fig. 8) across the diaphragm chamber divides the chamber into opposed pressure compartments 22, 23 for water pressing on the diaphragm. Said diaphragm is shown as stamped to provide annular ribs and intervening grooves 28, 29, to give the diaphragm a sinuous cross section to permit bending of the ribs to allow elongation of the diameter, and easy flexing

of the diaphragm to increase sensitivity, the chamber walls being provided with corresponding annular grooves 30 in which the ribs of the diaphragm may nest, to prevent injury to the diaphragm under pressure. Clamping means such as stud bolts 33 passing through the edges of one of the diaphragm wall portions into the other serve for clamping the edge of the diaphragm therebetween.

Said outer member 19 is provided with an outer passage 34 (Fig. 8) and an intermediate chamber 35 aligned and coaxial with the diaphragm chamber, a bushing ring 36 in the end of the intermediate chamber adjacent to the diaphragm chamber forming an inner passage 37. The outer end of the outer member is provided with a lateral flange portion 38 (Fig. 3) to which may be secured an upright conduit 39 (Fig. 5) having an air chamber 40 at its upper end, and a laterally curved lower portion provided with a flange 41 secured to said flange portion 38.

Said outer and inner members 18, 19 are provided with outer and inner upright pressure conduits 43, 44 (Figs. 1 and 8) communicating with said surge conduit 14 and outer passage 34 respectively, and a connecting passage 45 cooperating with telescoped pipes 46, 47 soldered together as at 48 to connect the conduits 43, 44 to communicate pressure in the riser and surge conduit to both of said diaphragm pressure compartments 30 and the air chamber.

The lower part of said outer pressure conduit 44 is enlarged at its lower end to form a valve chamber 50 communicating with said connecting passage, and forming an upper valve seat 51, and a lower threaded end 52 receiving a threaded plug 53 having an integral nut 56. The nut 56 is grooved and has a rotatable ring 54, secured by a chain 55 to the body 19, so that the plug 53 is held to body when removed. The plug 53 is provided with an upper projection 57 in the valve chamber provided with a vertical guide bore 58 slidably receiving the lower stem 59 of a constricting valve member having an upper tapered head 60 engaged with said seat 51.

A spring 62 compressed between said head and plug presses said head on the seat and holds the valve to said seat under all conditions. Said valve member is formed with an axial bore 63 and lateral bores 64 communicating therewith. A die 65 in the enlarged upper part of the axial bore is provided with a small axial aperture 66 cooperating with the bores 63 and 64 to provide an intermediate constricted passage allowing water and pressure to pass slowly to or from the air chamber until equilibrium is reached.

The outer member 19 is provided with cut off valves 67 and 68 (Figs. 5 and 9) on both sides respectively of the constricting member 59, 60 said valves being disposed in bores transverse to the pressure conduit 44 and connecting conduit 45. Each of said bores is formed with a reduced tapered inner end 69 intersecting the conduit, and with a threaded outer end 70 (Fig. 9) receiving a screw plug 71 having an axial bore receiving a stem 72 of a valve member 73 and having a transverse bore 74 in said tapered end 73. A compressible cup packing 75 on said stem is compressed between said plug and head, yieldably holds the head in its seat, and prevents leakage past stem 72. A manipulating arm 76 carried on the outer end of the stem is limited in its angular movement by stop pins 77, 78 (Fig. 1) and is disposed in non-projecting position against the pin 78 when the valve does not close the conduit, and

is disposed, when the valve closes the conduit against the pin 77 in laterally projecting position for a reason to be explained hereinafter.

A plunger rod 80 (Fig. 8) secured axially to 5 said diaphragm is guided axially of said passage 34 in a guide disk 81 in said passage having a central guide opening receiving the rod, and having intra-marginal perforations 82 to allow passage of liquid in the passage. Said outer body 10 19 has a large lateral opening 84 (Fig. 9) communicating with said chamber 35. A supporting plate 85 secured by screws 86 on the side of said outer member has a large opening registering with said lateral opening, and receives thereon a 15 thick cup-shaped rubber fulcrum member 87 having an outer flange 88 flat on the outer face of said plate, and provided with an inner neck 89 having narrow opening therein. A clamping plate-member 90 is clamped, by screws 86, on the outer face of said flange 88 and has an inwardly 20 pointing central tubular part 91 received in the cup member 87 secured thereon by wire bound around the cup. A lever 93, 94 mounted in a liquid-tight manner in said neck 89 is thereby intermediate fulcrumed, and has an electrically 25 insulated outer contact end 93, an inner motive end 94 received in an opening 95 of the plunger rod 80. The neck 89 is bound by wire 96 into fluid-tight contact with the lever.

30 An adjustable plate 98 (Fig. 1) slidably mounted on said supporting plate 85 is adjusted by means of an adjusting screw 99 and carries a double pole spring switch 100, 101, corresponding members 100 of each switch being extended and 35 connected with, and insulated from, each other by a block 102, one of the members 100 being normally just out of contact with, and engageable by, said insulated active end 93.

A partly cylindrical housing 104, 105 (Figs. 1 40 and 2) has a large inner end 106 and a smaller outer end 107 respectively fitting on said flange portions 25, 38, said ends having inner ribs 109, 110 at the inner face of the flange portions to prevent end-wise displacement of the housing. 45 Said housing comprises a pair of longitudinally divided halves or sections 104, 105 marginally rabbeted to form lapped adjacent edges 112, (Fig. 2) and provided with clamping brackets near said edges 113 receiving wing-headed clamping 50 screws 114 passing through said brackets, whereby the halves may be clamped on the flanges 25, 38 with the edges 112 well lapped.

A pair of spaced insulated projections 117 on the inner face of said sections adjacent to the 55 lapped joint 112 receive therebetween a normally closed spring supervising or tamper-switch 118 carried on said supporting plate 85 and adapted to be engaged and held closed by said projections 117 when the half sections are clamped closed 60 and to be allowed by the projections to open before the lapped portions 112 of the joint are entirely unlapped thereby to prevent access to the switch until it is open.

A supporting bracket 120 (Fig. 3) on the upper 65 part of said wall flange 25 carries a cable 121 mounted therein and extending out through an opening at the lapped joint of the housing. A terminal plate 122 mounted on the upper part of the outer member 19 has terminal screws, wires 70 from said cable and screws being for the purpose of connecting said detector switch 100, 101 in a suitable flow detector alarm circuit, and said supervising switch 118 in a closed supervising circuit for indicating whenever the housing is re- 75 moved. Said systems may be any suitable or

well known system, the switches being normally open or closed as the system requires.

The operation will be easily understood by those skilled in this art. Water hammer causes a sudden surge of high pressure in the riser 10; 5 and this sudden surge or other sudden high pressure in the riser cannot pass quickly through the constriction 65 (Fig. 8) to the chambers 23, 40, but is immediately communicated through the surge conduit 14 to the chamber portion 22 and 10 the diaphragm, causing the diaphragm to move the active lever 93 (Figs. 1 and 9) away from the switches 100, 101 to leave the switches open and the alarm inoperative. On the other hand, discharge by the sprinkler heads, as during a fire 15 causes a decrease in pressure in the riser, above the valve 15 (Fig. 5). This or any other sudden decrease in pressure in the riser causes the pressure in the chamber portion 22 to decrease immediately, while pressure from the air chamber 20 40 is still transmitted to the diaphragm, and this causes the lever-end 93 to engage the switches 100, 101 thereby to close the switches to energize said alarm means thereby to operate the alarm.

The restricted by-pass 65 permits slow equalization of pressure on both sides of the diaphragm, but will not during sprinkler discharge permit equalization, until after the lever 93, 94 has had time to cause the alarm.

The threaded outer end 53' (Fig. 8) of the plug 53 may be screwed into the part 52, whereupon the valves 67, 68 can be opened to rapidly fill the device. After filling the valves 67, 68 are closed, plug 53 assembled (as in Fig. 8), and the valves 35 67, 68 again opened. With the plug 53 removed from the threads 52, the covers 105 cannot be replaced.

The chamber portions 22, 23 may be kept normally entirely or partially filled with water or 40 air, as found most desirable.

In devices of this kind, it is sometimes necessary to clean or adjust the constricting member 59, 60, 65 (Fig. 8); and this can be done by removing the plug 53 and associated parts in the 45 enlargement 50.

When doing this it is usually desirable to cut off the water from the riser, which can be done by moving the handle 76 (Fig. 1) to the projecting position of the full lines. Also it is often 50 desirable to remove the constricting member without draining the chambers 23, 35, 40; and this can be done by turning the handle 76 of valve 67 to projecting position.

These manipulations, of course, require that 55 the housing 104, 105 be removed, thus opening the switch 118, sending a signal that the housing is not in place. This housing cannot be replaced so as to close the switch 118 until the projecting handles 76 and the plug 52 have been re- 60 stored to their proper places within the confines of the housing when entirely in closed, tamper-switch-closing, position.

The cup 87 and lever 93, 94 and associated parts may also be removed when the valve 68 is closed; but they must be replaced before the valve 68 is opened, else the housing would be flooded. Therefore, a signal that the switch 118 is closed, also indicates that the fulcrum cap and associated lever are in place.

When the system is operated without the city 70 check valve 15 or when the check valve leaks or when there are a plurality of communicating branch conduits 10', 10" (Fig. 10) fed from a single supply conduit M, it may happen that 75

near-by water discharge in a neighboring communicating conduit (as by a city fire hydrant or sprinklers of another branch conduit) may appreciably lower pressure at a pressure detector. To prevent this from sending a false alarm, the system shown diagrammatically in Fig. 10 is provided. This system takes advantage of the fact that such near-by water discharge causes a back flow of water in the conduit 10' or 10" when the pressure is lowered.

In Fig. 10 is shown a supply conduit M supplying branch conduits 10', 10" communicating therewith, each branch conduit having a pressure controlled detector, as in Fig. 1, communicating therewith. The double detector switch 100, 101 as shown in Fig. 1 associated with each detector comprises a normally open shunt switch 100, 101 and a normally open local switch 100', 101' both adapted to be closed by the lever end 83 when pressure decreases in the branch conduit. A local alarm circuit 122 for each branch 10' or 10" is closed by said local switch 100', 101' when operated, to notify the local attendant.

The supervisory alarm circuit for each pressure detector includes a current source 125, a normally closed tamper switch 118, a slow release relay 126 and a resistance 127 connected in series by conductors 128, 129, 130, 131 and controls a supervisory alarm circuit switch 133 operated by said relay when released. It is understood that the showing of the relay 126 and other parts therein are merely illustrative and that other alarm means, circuits and parts may be used. Shunt conductors 134, 135 connect said shunt switches 100, 101 around said relay 126 and resistance 127, to short circuit and cut out the relay when the shunt switch 100, 101 closes when the associated sprinkler heads discharge. To prevent operation of the relay from lowered pressure in other conduits, I provide a flow detector 138 in each of said branch conduits, here but not necessarily shown between the pressure controlled detector and the supply conduit.

Normally closed flow detector switches 139 interposed in said shunts 135 respectively are opened by said flow detectors when flow toward the supply main M takes place, to prevent the short circuiting of the relay 126 and operation of said supervisory alarm from back flow caused by water discharge or pressure reduction in other communicating conduits.

Should the cover 104, 105 be removed current in conductor 130 and associated relay 126 is interrupted, causing operation of the associated supervisory alarm.

Sometimes when there is a particularly violent water-hammer surge, the upward surge opens the valve 15 and causes a rise in pressure above the valve 15, which will cause an excessive rise in pressure above said valve much greater than normal.

This would cause a great difference in pressure between the conduit 14 and the chambers 40 and 23, which difference might interfere with the proper working of the apparatus before it could be equalized through the aperture 68. To prevent this interference there may be provided a by-pass 145, 146 (Fig. 11) around the apertured head 60.

This by-pass 145, 146 communicates with the conduits 45', 39' and is provided intermediately with a ball check valve 147 opening toward the air chamber 40 and pressed on its seat by a spring 148 compressed between the ball and a screw plug 149 in a threaded opening through

which the valve and spring may be inserted or removed. This spring 148 is strong enough to hold the ball valve in closed position except when sudden excess pressure in the upper part of the pipe 10, communicated through the duct 14 and by-pass section 145, lifts the ball valve from its seat and communicates equalizing pressure to the chamber 40.

On the other hand sudden lowered pressure in the upper part of the pipe 10 will merely cause the ball valve 147 to remain pressed closed; and the diaphragm 26 will be operated as heretofore described.

Instead of the two valves 67, 68, I may provide valves 67', 67" in the upper ends of conduits 45' and 45 and a three way valve 150 at the riser end of section 145 (Fig. 11) may be used. In the position of the drawings, the system is in operative condition. When the valves 67', 67" are open and valve 150 is turned to position to point the branch duct 151 directly downwardly, the duct 43' is closed so that plugs 53 and 149 may be removed and all parts of the apparatus except ducts 14 and 43' and inner chamber 22 may be drained through the openings from which the plugs were removed. When the branch duct 151 is turned directly leftward, the ducts 14, 43' may be drained through outlet 152 without draining chambers 23 and 40. When the valves 67', 67" are closed and the branch duct 151 is downward the members 60 and 147 may be removed without draining chambers 22, 23, 35 or 40.

Fig. 12 shows a somewhat simplified arrangement in which the apertured tapered head 60 is reversed to serve as a relief check valve in the place of the ball valve 147 of Fig. 11. In Fig. 12, the seat 51' for the tapered head 60 is placed in the end of the conduit 45" which connects the conduit 43 with the conduit 44". The tapered head 60, plug 53 and connecting parts are the same as in the previous figures except that the location and direction are changed and the spring 62' is made weak enough to release the head 60 from the valve seat when sudden pressure in the upper part of the pipe 10 is excessive, but strong enough to hold the head 60 on its seat during normal conditions and operation, so that the aperture 68 functions as in the previous figures.

A valve 67 may be interposed in the upper part of the conduit 44"; and when this valve 67 is closed, and the branch conduit 151 of the member 160 (Fig. 12) is rightward, the parts 53 and 60 may be removed without draining chambers 22, 23, 35 and 40.

In Fig. 12 the three-way valve 150' is interposed intermediately of the conduit 45" and when the valve is as shown in Fig. 11, the apparatus is in condition for normal operation. If it be desired to drain the air chamber 40, the passage 151 is turned toward the head 60, thus closing access to the conduits 43 and 14 permitting drainage through the outlet 152. If it be desired to drain the parts to the left of the three way valve while maintaining the air chamber under pressure, the passage 151 is turned toward the passage 43, thus closing the chambers 23 and 40, but allowing conduits 14 and 43 to drain.

The valve 150' is shown controlled by a hand wheel 165 having a cut-out 166 in the periphery which allows the cover 105' to be secured in place when the two-way valve is in normal position and the anchored plug 53 is in place. If the plug is out of place or if the valve 150' is not in normal position, the cover 105' is thereby prevented from being secured in place. It is understood that

Figs. 5, 11 and 12 are very diagrammatic for purposes of illustration.

In the form of invention shown in Fig. 13, the by-pass 44a, 45a shunts around said pressure operated diaphragm, and a flow-retarding apertured member 60 is interposed in said by-pass means as in Fig. 12; but an additional shunt conduit 145 serves as a by-pass around the apertured member 60; and a removable check valve 147 in said shunt conduit 145 opens toward said chamber 40, and operates as described of the device of Fig. 11.

In Fig. 13 there is a hand shut off valve 68 in said by-pass 45a between said shunt conduit 145a and the riser end of said by-pass, and a hand valve 67 in said by-pass between said air chamber 40 and said shunt conduit 145a.

The manipulation for clearing the valves 60 and 147 of Fig. 13 is the same as in Fig. 5, except that closure of both valves 67 and 68 permits removal of both valves 60 and 147.

In the device of Figs. 14 to 16, the by-pass 44b, 45b around the pressure operated diaphragm is provided with an intermediate valve seat chamber 159 (Fig. 15), receiving a three way valve member 160 provided with an axial chamber 161 having a valve seat 162 at the inner end, and an inner port 163 normally connecting said inner end with the by-pass portion 45b, and an outer port 165 normally connecting the outer end part of the chamber 161 with the outer by-pass portion 44b. The removable plug 53 is the same as in Fig. 8 and is screwed in the outer end of said chamber 161, and a similar spring 62 compressed between said plug and the constricting valve member 60 holds the valve member on the seat 162 and allows it to yield toward said outer end of the chamber 161, giving the member 60, the same function as described of Fig. 12.

Said valve seat chamber 159 has a lower drain duct 167 (Fig. 14) adapted at times to register with port 163 or 165 or a branch port 168 in said three way member communicating with said chamber 161.

Said member 160 is adapted when in the position shown to leave the by-pass 44b, 45b unobstructed (except for the apertured member 60) for normal operation. When in position with the port 163 down, it connects both end parts 44b and 45b of the by-pass with said drain duct 167. When in position with ports inclined at 45 degrees both end parts of the by-pass are closed to allow removal of the plug 53 and check valve member without draining the apparatus. A handle 170 on the valve member may be positioned to prevent the securing of the cover in place except in normal position of the valve member.

If the port 163 is turned down, the whole apparatus may be drained. If the port 165 is turned down, the duct 43 may be drained without draining the chamber 40. If the port 168 is turned down, the chamber 40 may be drained without draining the duct 43.

I claim as my invention:

1. In combination, an attachment for the fluid pressure line of a sprinkler system comprising a casing having an attaching portion, said casing having therein a surge passage which extends through said portion for communication with the interior of the line; means forming a by-pass around a part of the passage, said by-pass having therein a seat and there being a threaded opening associated with said seat; removable by-pass constricting means having an apertured head engaged on said seat, a threaded plug en-

gaged with the threads of said opening, and a compressed spring disposed between said plug and said head whereby to urge the latter against its seat.

2. In combination, a device adapted for attachment to the fluid pressure line of a sprinkler system comprising a casing having an attaching portion, said casing having therein a surge passage which extends through said portion for communication with the interior of the line; means forming a by-pass which has its opposite ends communicating with the passage, said by-pass having therein a seat and there being a threaded opening leading to said seat, said opening having threads on its boundary face; removable by-pass constricting means having an apertured head engaged on said seat, a threaded plug engaged with the threads of said opening, spring means disposed between said plug and said head and urging the latter to its seat, and a pair of cut-off valves for closing said by-pass, one valve being on each side of said constricting means.

3. A detector comprising a surge passage adapted to communicate with a riser and provided with a yielding pressure opposing means at its outer part; pressure operated means disposed across said passage and adapted to be pressed in opposite directions by pressure in said passage; means forming a by-pass conduit for said passage around said pressure operated means; a translating means controlled by the pressure operated means; said by-pass conduit being provided with a lateral opening and a closure therefor; and a removable member interposed in said by-pass conduit and removable through said opening and provided with a constricting orifice.

4. A detector comprising a surge passage adapted to communicate with a riser and provided with a yielding pressure opposing means at its outer part; pressure operated means disposed across said passage and adapted to be pressed in opposite directions by pressure in said passage; means forming a by-pass conduit for said passage around said pressure operated means; a translating means controlled by the pressure operated means; said by-pass conduit having a lateral opening and a closure therefor; a removable member interposed in said by-pass conduit and provided with a constricting orifice, said member being removable through said opening to allow cleaning of the orifice; and cut-off valves in said by-pass conduit on each side of said member respectively closing the ends of the by-pass conduit during cleaning.

5. In a detector, in combination, a body passage adapted to communicate with a riser and provided with a yielding pressure opposing means, and pressure operated means adapted to be pressed in opposite directions by pressure in said passage; a translating means controlled by the pressure operated means; a portion of said passage being enlarged to form a valve seat; a constricting valve in said portion engaged with said seat and provided with a constricted passage therethrough; a removable plug in said enlarged portion; and a spring between the plug and valve to yieldably hold said valve in place.

6. A detector comprising a surge passage adapted to communicate with a riser and provided with a yielding pressure opposing means at its outer part; pressure operated means disposed across said passage and adapted to be pressed in opposite directions by pressure in said

passage; a translating means controlled by the pressure operated means; structure means forming a by-pass for said passage around said pressure operated means and an intermediate chamber portion in the by-pass; a chambered valve member interposed in said intermediate portion and provided with an axial chamber having a valve seat at the inner end, an inner port normally connecting said inner end with the riser 10 end of the by-pass, and an outer port normally

connecting the outer part of the chamber with the outer part of the by-pass; a removable apertured constricting check valve member engaged with said seat and yieldable toward the outer end of said chamber; said ports being positioned 5 and adapted when in one position of the chambered member to leave the by-pass unobstructed for normal operation, and when in another position to close both end parts of the by-pass.
